UNITED STATES PATENT OFFICE.

HIRAM M. SMITH, OF RICHMOND, VIRGINIA.

MACHINE FOR CLEANING PEANUTS.

SPECIFICATION forming part of Letters Patent No. 350,326, dated October 5, 1886.

Application filed February 19, 1885. Renewed July 13, 1886. Serial No. 207,946. (No model.)

To all whom it may concern:

Be it known that I, HIRAM M. SMITH, a citizen of the United States, residing at Richmond, in the county of Henrico and State of Virginia, have invented certain new and useful Improvements in Machines for Cleaning Peanuts, of which the following is a specification, reference being had therein to the accompanying drawings.

10 Figure 1 is a longitudinal section of my improved separator for cleaning peanuts, taken on the line 1 1, Fig. 2. Fig. 2 is a transverse section on the line 2 2, Fig. 1. Fig. 3 is a top plan view. Fig. 4 illustrates the method of attaching the teeth or fingers to the reciprocating bar L. Fig. 5 is a detached view in section, showing the method of supporting the reciprocating bar at one end.

15 In the drawings similar letters of reference indicate like parts in all the figures.

The casing of the machine consists of uprights A A, top cross-girts, B B, bottom cross-girt, C, the side walls, D D, and the curved end wall, E, these parts being of the ordinary 20 form commonly in use in grain-separators.

25 F is a shaft carrying the fan-blades f, and provided at one end with a crank pulley or pinion, G, by means of which power may be applied from any desired motor, and at the opposite end with a crank-wheel, H, of peculiar construction, to be described. To the wrist-pin h of the crank-wheel is attached a bar, I, which at its opposite end is secured to arm k of the bell-crank lever K. Through these 30 devices a reciprocating motion is imparted to a feeder which extends across the machine and is supported at one end upon arm k' of the bell-crank K, and at its opposite end upon the rock-arm O, which in turn is attached to one 35 of the uprights A.

40 M is a board mounted in the upper part of the machine and forming the top wall of the fan-case. It slopes rearwardly and downwardly and forms, together with the side casing-walls and the opposing sloping board M', the feed-hopper of the machine.

45 The feeder consists of a reciprocating bar, L, situated at the bottom of and in close proximity to the board M, and forming practically a continuation thereof, it being situated in the same plane as the board, and carrying a series

of fingers or teeth, N, extending rearwardly and below the opening m, through which the peanuts are fed from the hopper into the machine. The bar L and its fingers form a feeder 55 which insures that the peanuts shall be fed into the machine at a continuous and uniform rate.

In Fig. 4 is illustrated a method of attaching the fingers or teeth, which are preferably formed of heavy wire, to the reciprocating bar. Before securing it to the bar the tooth is of the form shown—that is, it consists of the longer part, n, a short portion, n', at right angles thereto, and another short part, n'', parallel 65 with the portion n. The wire bent into this shape is then passed through apertures l', formed in the bar for its reception, the longer arm, n, passing through the hole nearest the front edge of the bar. After the part n' of the wire has 70 been drawn up close to the under side of the bar, a groove being formed for its reception, if preferred, the projecting end of part n'' is bent down, as at n'', and the part n bent to form the projecting finger. By this method 75 I am enabled to rapidly, securely, and cheaply attach the teeth to the bar.

In order to give the bar L the proper inclination, I interpose a block, P, preferably of cast-iron, between the end of the bar and the 80 rock-arm O, which supports it, this block being wedge-shaped and provided with a stud, p, which drops into a hole formed for its reception in the arm O, the bar L being secured to the upper surface of the block by screws or 85 otherwise. (See Fig. 5.) The other end of bar L is secured to rock-arm k' by means of a stud rising from the arm and fitting into a hole in the bar formed for its reception. The weight of the bar L and the material resting 90 upon it, and which it operates to feed into the machine, is borne entirely by the arms k' and O, and their supporting-pivots.

I have found that the various conditions under which the machine is used necessitate 95 that means should be employed for changing somewhat the direction of the air-currents, and I have shown an arrangement of wind-deflecting boards in rear of the fan, which I now deem best suited to the requirements of 100 the machine.

R R' is a deflecting-board below the opening

m in the feed-hopper, operating to guide upwardly the air from the fan and cause it to operate upon the stream of peanuts and remove therefrom the dirt and impurities, as well as the light imperfect peas contained in the mass fed into the hopper. The peanuts fall upon the board *R R'*, which guides them to the discharge-opening *S*. This deflector-board is formed in two parts, *R R'*, hinged 10 along the line *r*, and is loosely placed between the two side walls of the casing of the machine, where it is held in any position to which it may be adjusted by drawing the side casing-walls against the edges of the deflector, in a 15 manner to be hereinafter explained. The lower edge of the part *R* of the deflector-board rests upon the board *y*, along which it may move as the board is being adjusted. This method of mounting the deflector or wind 20 board within the machine permits it to be longitudinally adjusted—that is, in the direction of its length—toward or from the tail wind-board *u*, and vertically adjusted toward or from the opening from the feed-hopper, and permits it to be variously inclined, all of these 25 changes being made by the board as a whole—that is, without bending along the line *r*; or one part, *R* or *R'*, may be moved without a corresponding change in the position of the 30 other part. This capability of various changes of position I have found very desirable, owing to the different grades of material operated upon, or the different kinds of work required of the machine, one position wherein the two 35 parts *R R'* lie in different planes being shown in dotted lines, Fig. 1.

When the board is lowered into the position indicated in dotted lines, the peanuts have farther to fall before striking the inclined 40 board, and hence are longer exposed to the direct influence of the air-current than they are when the board is raised, while after reaching the board they travel more slowly, owing to the less inclination of the guide-board *R*.

45 *u* is a tail-board, which, as will be readily understood, is tilted or adjusted to correspond with the position of the deflector *R R'*.

I have shown a novel method of fastening the board in its various adjusted positions, it 50 consisting of a rod, *T*, passing through the machine from the outside of one casing-wall *D* to the other. It is provided at one end with a head, *t*, and at the opposite end with a thumb-nut, *t'*, by turning which I can draw 55 the head *t* and the nut tightly against the side casing-walls, and thus hold the boards in any desired position by compression, or drawing together the thin sides or walls of the casing, the rod *T* being placed beyond the limit ac-

60 tually reached by the boards. Each part of the divided board, as well as the other movable wind-deflectors in the machine, may be provided with one of these adjusting-rods. This adjustable deflector is mounted perfectly 65 free between the walls of the casing and between the front and rear uprights, *A*, and serves, when secured in place by reason of the

casing being drawn against the edges of the board by the bolt *T*, both as a guide for the material being cleansed, and also as a cross-brace for the machine between the front and rear upright posts, *A*. 70

V W X are deflecting-boards adapted to form a contracted throat from the fan and to guide the air against the material being fed 75 into the machine. If desired, the board *W* may be arranged to swing into various positions. The crank-wheel *H* is provided with a flange, *h'*, around its periphery, whereby there is formed a pulley adapted to receive a belt, 80 *Z*. The wrist-pin *h* is sufficiently long to project beyond the flange, so that it and the connecting-rod *I* will not interfere with the belt, which latter may pass to and operate a separator of the endless-belt pattern, often used in 85 combination with the machine just described, and to which the peanuts are delivered after passing through the separator.

I do not wish to be limited to the employment of the various features described in a 90 peanut-separator, as they may be advantageously employed in machines adapted to clean other materials; nor do I wish to be limited to the precise form of casing shown, nor the particular mechanism for reciprocating bar *L*, as 95 these may be of any of the well-known or preferred kinds.

What I claim is—

1. In a separator, the combination of the hopper, the reciprocating bar *L*, the teeth or 100 fingers carried by said bar, each consisting of the short portion *n'* below the bar, the short portion *n''*, passing upward through the bar, and having its end bent to lie on the top of 105 the bar, as at *n'*, and the longer part, *n*, passing through the bar and bent to form the finger *N*, which lies below the opening from the hopper, and mechanism for reciprocating the bar, substantially as set forth.

2. In a separator, the combination of a hopper, feeder, rock-arms which support the 110 feeder, and a wedge-shaped block, *P*, situated between the feeder and one of its supporting rocking arms, whereby the feeder is inclined relatively to its supporting-arms, and means 115 for reciprocating the feeder, substantially as set forth.

3. In a separator, the combination of the casing, the hopper, the rocking arms, the reciprocating bar *L*, supported at its ends upon 120 the rocking arms, the wedge-shaped block *P*, situated between one of the rocking arms and the reciprocating bar, it being provided with a pin, *p*, which enters a hole in the rocking arm, and means for reciprocating the bar, substantially as set forth. 125

4. In a separator, the combination of the casing, the feed-hopper, the fan, a deflecting-board mounted between the side walls of the casing in rear of the fan and below the opening *m* from the hopper, and being loosely placed between the side walls of the casing, whereby it may be longitudinally adjusted in 130 the direction of its length and vertically ad-

justed toward and from the feed-opening m , and the nutted screw-rod T , passing through the machine and adapted to draw the casing-walls against the edges of the deflector-board, to hold it in place after adjustment, said rod being placed at the limit of vertical adjustment of the said board, substantially as set forth.

5. In a separator, the combination of the casing, the fan, the feed-hopper, and a deflecting-board situated in rear of the fan and below the feed-opening from the hopper, it being composed of two parts, $R R'$, hinged together, the two parts being capable of separate adjustment, substantially as set forth.

6. In a separator, the combination of the 15 casing, the fan, the hopper, and adjustable deflecting wind-board situated below the hopper and formed of two parts hinged together, and the tail wind-board u , substantially as set forth.

20 In testimony whereof I affix my signature in presence of two witnesses.

HIRAM M. SMITH.
